UNITED STATES PATENT OFFICE.

CARLTON H. ALLEN, OF DAYTON, OHIO.

PROCESS AND APPARATUS FOR MAKING PAPER OR THE LIKE.

Application filed January 11, 1926. Serial No. 80,585.

This invention relates to a process and apparatus for making paper.

The objects attained in the practice of the invention consist in an improved method for proportioning, mixing and furnishing the paper making machine with paper stock and for recovering broke and overflow stock from the machine and returning it to the stock circulating system in a coordinated apparatus.

In preferred form of the apparatus the furnish (paper stock) for the paper making machine is prepared as to the mixing of the ingredients in a continuous flow controlled by automatic meters as distinguished from preparing the different ingredients in batches and mixing by the well known methods of the common practice.

The use of automatic meters, which in their preferred form are timed by a direct connection to the speed of the paper making machine, results in the weight of the sheet being thus held more uniformly and closely to the desired figure, with the further result that changes in the furnish can be made without a break in the paper. The meters being directly driven from and discharging directly to the paper machine fan pump, the machine chest and stuff pump, now always essential elements in the process, are eliminated, there being no intermediate storage of paper stock.

Where automatic meters are used in the arrangement herein described it is unnecessary when changing from one furnish to another, to first run out the stock in the machine chest, thus enabling the operator to instantly correct any error in the proportions of ingredients and obtaining the highest possible uniformity and quality in the paper. The effect of the adjustments in the furnish of the auxiliary ingredients is almost immediately apparent on the paper machine. The improved method also results in a decrease in the amount of broke stock and an increase in the tonnage of salable paper per unit of time. This is not possible when a reservoir of paper stock is used as in the common practice.

A further object attained in the invention consists in the elimination of various other stock chests or tanks and intermediate stock moving equipment used in the common practice and in substituting therefor direct-action equipment which is less cumbersome and more effective to maintain uniformity

of movement of the stock, thus having a beneficial effect on the regularity in weight and quality of the paper produced.

The coordinated stock recovery system which is a feature of the invention minimizes the importance of the human element in the functioning of the apparatus in this respect and also reduces to a minimum the possible stock losses through overflows, etc., to the mill drains.

To these gains in the quality, quantity and cost of production are added the further mechanical advantages of a simplified apparatus which is lower in first cost and in maintenance cost and requires less installation space than ordinary paper mill equipment. The importance of these results will be obvious to experienced paper makers.

My invention is herein illustrated and described both as an improved process for making paper and suitable apparatus in a preferred form for practicing the invention, the accompanying drawings serving to illustrate the coordinated apparatus and also detail features of certain of its novel structural units, the invention being defined in the appended claims within the limitations of the illustrations and also in the broader aspects contemplated in its general practice with any suitable apparatus.

In the drawings:

Fig. 1 is a diagrammatic view in elevation illustrating an apparatus in preferred form suitable for practicing the invention;

Fig. 2 is a detail view in elevation illustrating the operating connection between the Fourdrinier and the automatic stock proportioning meter;

Fig. 3 is a plan view of the parts illustrated in Fig. 2;

Fig. 4 is a detail in elevation, partly in section, of the automatic stock proportioning meter;

Fig. 5 is a plan view of the structural features illustrated in Fig. 4;

Figs. 6 and 7 are views illustrating further detail features of the stock proportioning meter;

Fig. 8 is a detail view of a group unit of the paper making apparatus comprising a stock storage tank, pump suction box, pump and stock consistency regulator;

Fig. 9 is a transverse section through the couch pit;

Fig. 10 is a side elevation partly in section of the broke stock regulating box;

Fig. 11 is a plan view of the broke stock regulating box.

As here shown in Fig. 1 the ground wood slush storage 3 is located on a floor 2 below the main floor 1, the stock moving from the storage by gravity to a pump suction box 4, it being understood that the arrow-head lines throughout the figure represent pipe lines connecting the different units of the apparatus one with another.

A regulator 5 of well known construction is used, as here shown, for regulating the consistency of the stock as it passes through pump 6, which acts to transfer the stock from the suction box to the proportioning meters 9 where the additional ingredients as sulphite, soda, clay, alum, size color, etc., are added to effect a mixture of the required proportions for the kind and quality of paper to be produced.

An automatic stock proportioning meter embodying the principle of the meter here shown and combined in the preferred form of the invention comprises the subject matter of United States Patent No. 15,311 re-issued to me and Edward J. Trimble jointly, March 21, 1922. For a more ready understanding of the functions of the meter and its influence on the present invention, its main structural features are further illustrated in detail Figs. 2 to 7. It will be understood that the use of the automatic meters in connection with the present invention is considered in their broader aspects, that is to say, in any suitable form as may best serve the practice of the invention. For instance, certain of the paper stock ingredients, as size, alum, etc., in diluted liquid form can be added to the stock stream after it has passed the stock meters, the main characteristic being that the mixing of the ingredients is continuous with the proportions of ingredients, as made from time to time according to the kind and grade of paper to be made, maintained automatically.

The ground wood stock is delivered by pump 6 through line 7 into vat 11 of the stock proportioning meter 9, the sulphite soft stock being pumped in a similar manner from any suitable source (not shown) through line 7^a into vat 10 of the meter. The action on the stock in the meter with added ingredients will presently be described. The stock flows by gravity from the meter through line 12 to pump 13 and is delivered by the pump through line 14 to a screen 15, the overflow stock from the meter being returned through line 8 to the pump suction box 4. From the screen the stock moves by gravity through flow box 16 to the wire 17 of the paper making machine, the excess white water passing to the wire pit 18, these units including the pumps and screen being of a well known construction.

65 The broke stock from the Fourdrinier wire

passes to the couch pit 19, which is of special construction, the feature of novelty consisting of an angularly disposed screen 20 over the couch pit immediately below the couch roll 21 which acts to separate the excess broke stock from the white water which then flows by gravity through line 22 together with the overflow white water from the wire pit 18 to a cylinder save-all 25 of well known construction, the main discharge from the wire pit 18 being through gravity flow line 18^a to line 12. The broke stock flows over the screen by gravity and is conducted by gravity from the unscreened portion 26 of the couch pit through line 27 to a chest 28. To provide screen 15 with the maximum capacity the opening of the couch pit is extended, as here shown, to the full width of the pit, or of the paper making machine, thus the screen will have ample capacity for the heavy rush of paper stock at times when the stock is running over the Fourdrinier wire but is not being carried over from the couch roll to the first press.

The stock from the save-all cylinder is restored to the broke, or couch stock, in chest 28, a broke beater 29, preferably as here shown of the continuous extraction principle for reworking accumulations of broke stock from the main press, etc., also discharging direct into the chest. The stock from the chest is then transferred by a pump 30 through line 31 into a broke regulating box 32 and is thence returned by gravity through lines 33 and 8 to pump suction box 4. The clarified water from the cylinder save-all flows into a tank 34 and is then transferred by a pump 35 through line 36 to a shower pipe 37 disposed over the Fourdrinier wire adjacent the couch roll, the shower acting in a well known manner to flush and clean the wire.

Referring now to the structural features of the several units of mechanisms which have been combined in a novel relation in the co-ordinated action of the paper making apparatus.

The automatic stock consistency regulator 5 is of a well known type and its functions are well understood in the paper making industry. However, as here shown, the regulator sustains a novel relation to the stock circulating system, the closely related action of the three units, namely, the pump suction box 4, stock consistency regulator 5 and pump 6 being such that the additional stock chests and intermediate stock moving equipment ordinarily required are unnecessary; furthermore, as a result of the automatically maintained consistency of the stock and the constantly maintained head conditions at the pump, which results from the co-ordinated action of the three units, greater uniformity in the volume of the flow to the mixers and from the mixers to the paper making ma-

water and deliver the broke stock from the paper making machine under all ordinary conditions of operation.

In detail Figs. 10 and 11 a suitable construction is shown in one form for the broke stock regulator, the same consisting, as here shown, of a single unit meter similar in construction to the stock ingredient meter. The regulator consists of a vat 63 which receives the broke stock from line 31 the inlet to the vat being controlled by a float valve 64. The stock is delivered from the vat to a flow box 65 by a rotatable meter 66 driven, as here shown by a motor 67 through a suitable gear connection 68—69, the motor being controlled by a stop-and-start switch 70 which in turn is connected to the float valve 64. The stock is delivered from flow box 65 by gravity through line 33, to overflow line 8, and thence through line 4^a to the pump suction box 4.

From the foregoing detailed description of the improved process and the diagram of the apparatus illustrated in Fig. 1, together with the illustrations of structural features in the detail figures, the practice of the invention and the advantages derived thereby will be understood by experienced paper makers.

It is noted that while the use of the automatic meters as herein shown adds to the effective operation of the improved system, they are not necessary to the practice of the invention with other forms of mixing apparatus, for example, the batch method of preparing the stock.

With respect to the novel screening feature employed at the couch pit, it is pointed out that a general fault and a source of constant stock loss in the common practice is thus corrected. Experience proves that it is difficult, to persuade machine tenders to dump the couch pits with regularity. When the paper on the machine is running well, the dumping of the couch pit full of stock results in changing the weight of the sheet, and when there is a break in the paper, the machine crew is usually too much occupied to give attention to the couch pit stock. Thus the couch pit is full of stock most of the time and the white water overflow carries a large portion of the accumulation away as waste to the mill drains. The improved couch pit, having reference to the function of the added screen, requires little or no attention and prevents excessive accumulation of stock and white water, no waste resulting, also the broke stock is directed to better advantage in the means provided to again deliver it through the return lines to the paper making machine.

The improved paper making system as a whole has proved highly effective in a number of paper mills where the invention is in daily operation. Its advantages, briefly

stated in summary, consisting in a simplified, lower cost apparatus, reduced operating overhead, direct action continuous operation, less waste, gain in output and in the quality of the product.

70

A novel feature combined with, the broke stock regulating box consists in associating with the meter a quantity register 71 of any suitable type which acts to register the quantity of broke stock passing through the meter 75 and thus to provide a record from which operating efficiency data can be computed.

75

Having described my invention, I claim:

1. The herein described process for making paper consisting in automatically effecting and maintaining the consistency of certain stock ingredients, as the ground wood pulp, near its source of supply, in effecting continuous delivery of the stock so regulated to a common stream for mixing stock ingredients, and in maintaining a continuous flow of the mixed stock directly to the paper making machine.

80

2. The herein described process for making paper consisting in automatically effecting and maintaining the consistency of certain stock ingredients, as the ground wood pulp, near its source of supply, in effecting constant uniformity of head pressure in the stock stream near said source of supply, in effecting continuous delivery of the stock so regulated to a common stream for mixing stock ingredients and in maintaining a continuous flow of the mixed stock direct to the paper making machine.

85

3. The herein described process for making paper consisting in automatically effecting and maintaining the consistency of certain stock ingredients, as the ground wood pulp, near its source of supply, in effecting continuous delivery of the stock so regulated to a common stream for mixing stock ingredients, and in maintaining a continuous flow of the mixed stock directly to the paper making machine and in returning broke stock 100 from the paper making machine to the stock circulating line at a point in advance of said regulation of the consistency of the stock.

95

4. The herein described process for making paper consisting in automatically effecting and maintaining the consistency of certain stock ingredients, as the ground wood pulp, near its source of supply, in effecting continuous delivery of the stock so regulated to a common stream for mixing stock ingredients, in maintaining a continuous flow of the mixed stock to the paper making machine and in returning broke stock from the paper making machine and overflow mixed stock 110 to the stock circulating line at a point in advance of said regulation of the consistency of the stock.

105

5. The herein described process for making paper consisting in automatically effect- 120

125

130

chine is obtained and paper of better quality is produced.

Structural features of the group unit of pulp storage tank, pump suction box, consistency regulator and pump are shown in detail Fig. 8. It will be observed that the individual units are all direct connected one with another, that a constant head is maintained in the suction box by the well known means as a float valve as indicated at 54 and that the consistency regulator is furnished with sample stock from line 7 through a line connection 55, it being understood that the supply of sample stock to the regulator is constant, the return flow being to the pump suction box. Also, the broke stock is returned to the supply line 4^a, intermediate the pulp storage tank and the suction box for the double purpose of maintaining uniformity in the consistency of the stock and to prevent flooding of the suction box. Thinning water for the stock is introduced through line 6^a at a point immediately adjacent the suction line connection to the pump, the volume of water delivered through line 6^a being automatically controlled by the consistency regulator. Effective means for maintaining constantly a high condition of consistency and uniform flow of the stock are provided in the coordinated action of the group unit.

Structural features of the automatic stock meter or mixer are illustrated in detail Figs. 2, 3, 4, 5, 6 and 7, Figs. 2 and 3 illustrating the direct operating connection in one form of the meter to the paper making machine which serves to maintain an invariable speed relation between the two units and therefore a balanced relation of the stock when the proportions of the ingredients have been determined at the meter, the volume of flow of the various ingredients through the meter being thus automatically regulated to the speed of the paper web through the paper machine.

Any suitable driving connection between the meter and Fourdrinier machine will serve to effect this regulation of the stock. As here shown in Figs. 2 and 3, the driving connection is from a gear 38 connected to the couch roll shaft, through an intermediate gear 39, shaft 40, belt pulleys 41-42, belt 43, variable speed pulleys 44, belt 45, belt pulleys 46-47, belt 48, clutch shaft 49, intermediate gears 50-52 to the main meters 53, the variable speed pulleys 44 being controlled by a belt shifter rod 54 for adjusting the relative speeds between the stock mixer and paper machine at the desired ratio according to the required rate of delivery of the stock to the machine. By means of this direct drive through the variable speed connection the thickness of the paper or weight of paper is brought to the desired figure by moving the belt shifter. Once

set, the quality of the paper does not change as to thickness or weight or composition. If the paper machine speeds up or slows down all of the individual ingredient meters speed up or slow down accordingly and thus hold the weight of the sheet, also the composition or quality of the paper, uniform regardless of fluctuations in the speed of the paper machine. This is highly important as it puts the weight, uniformity and quality of the paper under automatic control and better results are obtained than is possible by hand regulations as in the common practice, which require skill on the part of the operator.

As illustrated in Figs. 4 and 5 the main stock ingredients—ground wood pulp and sulphite—are delivered respectively from the receiving tanks 10-11 through the meters 53 into a flow box 56. Other ingredients, as size, color, alum, clay, etc., are also delivered, as here shown, in kind and quantity as required into flow box 56, all ingredients being then conducted through a second flow box 57, thorough mixing of the stock resulting from the interference between the stream lines of different ingredients as the same converge in a common stream through flow box 57 and line 12 to pump 13.

In detail Figs. 6 and 7 a single unit auxiliary meter is illustrated for supplying the various additional ingredients to the stock in flow box 56, each unit comprising, as here shown, a charging or receiving vat 58, the ingredients being supplied to the vat from any suitable source, a meter 59, a flow box 60 and a geared connection 61-62 to the main stock meters 53, an adjustable gate 62^a being provided at the meter to regulate the discharge opening. These structural features of automatic meters of the principle here illustrated are well known in the art and do not require further description in connection with the present invention. It will be understood that the meters, being direct connected and therefore timed to the speed of the paper making machine, act to regulate the stock ingredients as to volume and to converge the ingredients into a mixture in a continuous common stream in which intimate intermixing or blending of the stock takes place as it is conducted to the paper making machine.

It will be observed in the diagram Fig. 1 that pipe lines 12 and 14 are represented at 12^a as connected one with the other. This is for the purpose of flushing line 12, which is a gravity flow line and becomes clogged at times with the stock, from line 14, which is a pressure line, thus to maintain free movement of the stock.

It will be observed in Fig. 9 that the stock separating screen extends across the full width of the couch pit, ample capacity being thus provided to extract the white

- ing and maintaining the consistency of certain stock ingredients, as the ground wood pulp, near its source of supply, in effecting continuous delivery of the stock so regulated 5 to a common stream for mixing stock ingredients, in maintaining a continuous flow of the mixed stock to the paper making machine and in causing the flow of broke stock from the paper making machine to be equalized 10 and returned to the stock circulating line at a point in advance of said regulation of consistency of the stock.
6. The herein described process for making paper consisting in automatically effecting and maintaining the consistency of certain stock ingredients, as the ground wood pulp, near its source of supply, in effecting direct, continuous delivery of the stock so regulated under constant head pressure to 15 a common stream for mixing stock ingredients and in maintaining a continuous flow of the mixed stock directly to the paper making machine.
7. The herein described process for making paper consisting in causing the fluid stock ingredients to be mixed in a common stream as it advances to the paper making machine, in effecting separation of the excess white water from the broke stock as the 20 stock passes from the paper making machine, in recovering the stock in the white water, combining it again with the broke stock and redelivering the combined stock through return lines to the paper making machine.
8. The herein described process for making paper consisting in causing the fluid stock ingredients to be mixed in a common stream as it advances to the paper making machine, in effecting separation by gravity 25 of the excess white water from the broke stock as the stock passes from the paper making machine, in recovering the stock in the white water, combining it again with the broke stock and redelivering the combined stock through return lines to the paper making machine.
9. The herein described process for making paper consisting in causing the fluid stock ingredients to be mixed in a common stream as it advances to the paper making machine, in causing the broke stock as it 30 passes from the paper making machine to flow over a screen to effect separation by gravity of the excess white water from the stock, in recovering the stock in the white water, combining it again with the broke stock and redelivering the combined stock through return lines to the paper making machine.
10. The herein described process for making paper consisting in causing the fluid stock ingredients to be mixed in a common stream as it advances to the paper making machine, in effecting separation of the 35 excess white water from the broke stock as the stock passes from the couch roll of the paper making machine, in recovering the stock in the white water, combining it again with the broke stock and redelivering the combined stock to return lines of the paper making 40 machine at a point in advance of the mixing of the stock ingredients.
11. The herein described process for making paper consisting in causing the fluid stock ingredients to be mixed in a common stream as it advances to the paper making machine, in effecting separation of the excess white water from the broke stock as the stock passes from the couch roll of the machine, in recovering the stock in the white water, combining it again with the broke stock, in regulating the combined stock and redelivering it through return lines to said machine.
12. The herein described process for making paper consisting in causing the paper stock to pass over the wire of the paper making machine, in effecting separation of the excess white water from the broke stock as the stock passes from the couch roll of the machine, in recovering the stock in the white water, combining it again with the broke stock and redelivering the combined stock through return lines to the said machine.
13. The herein described process for making paper consisting in causing the paper stock to pass over the wire of the paper making machine, in causing the broke stock as it passes from the wire of the machine and the overflow from the wire pit to flow over a screen to effect separation by gravity of the excess white water from the stock, in recovering the stock in the white water, combining it again with the broke stock and redelivering the combined stock through return lines to said machine.
14. The herein described process for making paper consisting in causing the paper stock to pass over the wire of the paper making machine, in effecting separation of the excess white water from the broke stock as the stock passes from the couch roll of the machine, in recovering the stock in the white water, combining it again with the broke stock and redelivering the combined stock through return lines to the machine, and in causing a portion of the clarified white water to be discharged in a shower over the wire of said machine.
15. A paper making apparatus including in the combination of a paper stock circulating system, means to regulate the consistency of a stock ingredient, as the ground wood pulp, near its source of supply, means acting constantly to combine the regulated stock in a common stream for mixing stock ingredients flowing continuously direct to the paper making machine.
16. A paper making apparatus including in the combination of a paper stock circulat-

ing system, means to maintain a constant head pressure in the fluid of a stock ingredient, as the ground wood pulp, means to regulate the consistency of said ingredient, and 5 means acting constantly to combine the regulated stock in a common stream for mixing stock ingredients flowing continuously direct to the paper making machine.

17. A paper making apparatus including 10 in the combination of a paper stock circulating system, means to regulate the consistency of a stock ingredient, as the ground wood pulp, near its source of supply, means acting constantly to combine the regulated 15 stock in a common stream for mixing stock ingredients flowing continuously direct to the paper making machine and means for returning broke stock from said machine to the stock circulating line at a point in advance of said consistency regulating means.

18. A paper making apparatus including in the combination of a paper stock circulating system, means to regulate the consistency of a stock ingredient, as the ground 25 wood pulp, near its source of supply, means acting constantly to combine the regulated stock in a common stream for mixing stock ingredients flowing continuously to the paper making machine and means for equalizing the flow of broke stock from said machine and in returning said broke stock to the stock circulating line at a point in advance of said consistency regulating means.

19. A paper making apparatus including 35 in the combination of a paper stock circulating system, a continuous stock mixer, a gravity flow line for conveying the mixed stock to a given point, a pressure line for conveying the stock beyond said point, and 40 a connection between said lines for flushing the flow line from the pressure line.

20. A paper making apparatus including in the combination of a paper stock circulating system, a screen disposed in the flow 45 of broke stock from the paper making machine to the couch pit acting to separate the excess white water from the stock.

21. A paper making apparatus including in the combination of a paper stock circulating system, a screen disposed in the flow 50 of broke stock from the paper making machine to the couch pit acting to separate the excess white water from the stock and means to recover the stock in the diverted white 55 water.

22. A paper making apparatus including in the combination of a paper stock circulating system, a screen disposed in the flow of broke stock from the paper making machine 60 to the couch pit acting to separate the excess white water from the stock, means to recover the stock in the diverted white water and to restore it to the broke stock.

23. A paper making apparatus including 65 in the combination of a paper stock circu-

lating system, a screen disposed in the flow of broke stock from the paper making machine to the couch pit acting to separate the excess white water from the stock, means to recover the stock in the diverted white water 70 and to restore it to the broke stock and means to direct the combined stock to the return lines of the paper making machine.

24. A paper making apparatus including in the combination of a paper stock circulating system, a screen disposed in the flow of broke stock from the paper making machine to the couch pit acting to separate the excess white water from the stock, means to recover the stock in the diverted white water 80 and to discharge the clarified water in a shower over the return side wire of the paper making machine.

25. A paper making apparatus including in the combination of a paper stock circulating system, a screen disposed in the flow of the broke stock from the wire of the paper making machine and in the overflow from the wire pit to the couch pit acting to extract the excess white water from the stock. 85

26. The herein described process for making paper consisting in supplying the paper stock ingredients in diluted form to a common stream and in maintaining the composition and volume of flow of the stream directly to and in agreement with the instant and continuous demand of a paper making machine. 95

27. The herein described process for making paper consisting in supplying the paper stock ingredients in diluted form to a common stream flowing directly to a paper making machine and in causing the volume of flow of said stream to fluctuate proportionately to the variation in the instant and continuous stock requirement of said machine. 100

28. The herein described process for making paper consisting in supplying the ingredients in diluted form to a common stream and in preserving the continuity and direct 110 volume of flow of the stream between the point of composition of the stock and the paper making machine.

29. The herein described process for making paper consisting in supplying the ingredients in diluted form to a common stream in combining with said common stream a stream of return broke stock and preserving the continuity and direct flow of the combined stream from point of confluence to the 115 paper machine. 120

30. The herein described process for making paper consisting in supplying the ingredients in diluted form to a common stream and in joining with said common stream a stream of the broke stock and a stream of return water from the paper making machine preserving the continuity of the stream 125 from the point of said confluence to the paper making machine. 130

31. The herein described process for making paper consisting in causing the stock ingredients to be mixed in a common stream flowing directly to a paper making machine and in automatically synchronizing the volume of each of said elements preceding their confluence in said stream, with the movement of the newly formed paper web on said machine. 5
- 10 32. The herein described process for making paper consisting in causing the stock ingredients to be mixed in a common stream flowing directly to a paper making machine and in effecting a regulating relation between said elements preceding their confluence in said stream whereby the volume of flow of the stream will be automatically regulated to the paper stock requirement of the machine. 15
- 20 33. The herein described process for making paper consisting in causing the stock ingredients to be mixed in a common stream flowing directly to a paper making machine and in controlling automatically from said machine the volume of said elements at the point of their confluence into said stream whereby the volume of the flow will be coordinated to the paper stock requirement of the machine. 25
- 30 34. The herein described process for making paper consisting in causing the paper stock to flow continuously and directly to a paper making machine and in controlling automatically from said machine the volume of the flow according to the paper stock requirement of the machine. 35
- 40 35. A paper making apparatus comprising in combination, means to cause a common stream of paper stock ingredients to flow continuously and directly to a paper making machine and an operating connection between said means and said machine whereby the volume of the stream will be automatically regulated according to the stock requirements of the machine. 45
36. A paper making apparatus comprising in combination, means to cause a common stream of paper stock ingredients to flow continuously and directly to a paper making machine and an operating connection between said means and said machine whereby the volume of the stream will be automatically regulated according to the stock requirements of the machine, and means to return broke stock from the machine to said common stream. 50
37. A paper making apparatus comprising in combination, means to cause a common stream of paper stock ingredients to flow continuously to a paper making machine and an operating connection between said means and said machine whereby the volume of the stream will be automatically regulated according to the stock requirements of the machine, and means to regulate 55 and measure the volume of broke stock from said machine and return the same to said common stream. 60
38. The herein described process for making paper consisting in causing the paper stock ingredients to be proportioned and combined at a common point in the stock circulating system, in causing the combined stock to flow continuously and directly in a common stream from said point to the paper making machine to effect mixing of said ingredients. 65
39. The herein described process for making paper consisting in causing the paper stock ingredients to be proportioned and combined at a common point in the stock circulating system, in causing the combined stock to flow continuously and directly in a common stream from said point to the paper making machine to effect mixing of said ingredients and in causing the broke stock from said machine to be returned to the stock circulating system at a point in advance of said point for combining the stock 70 ingredients. 75
- In testimony whereof, I affix my signature.
CARLTON H. ALLEN. 80
